DESIGN FOR AN AUTOMOBILE TIRE

Harry C. Hower, Chicago, Ill.

Application December 31, 1934, Serial No. 54,648

Term of patent 7 years

To all whom it may concern:

Be it known that I, Harry C. Hower, a citizen of the United States, residing at Chicago, in the county of Cook and State of Illinois, have invented a new, original, and ornamental Design for an Automobile Tire, of which the following is a specification, reference being had to the accompanying drawing, forming a part thereof.

In the drawing, the single figure is a perspective view, partially in dotted lines, of a tire showing my new design.

I claim:

The ornamental design for an automobile tire, as shown.

In witness whereof, I hereunto subscribe my name this 27th day of December, 1934.

HARRY C. HOWER.
